UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

DESIGN FOR AN ELECTRICAL RECEPTACLE.

61,027.

Specification for Design.

Patented June 6, 1922.

Application filed November 26, 1920. Serial No. 426,661. Term of patent 7 years.

To all whom it may concern:—

Be it known that I, REUBEN B. BENJAMIN, a citizen of the United States, residing at Chicago, in the county of Cook and State of Illinois, have invented a certain new, original, and ornamental Design for an Electrical Receptacle, of which the following is a specification, reference being had to the accompanying drawing, forming a part thereof.

Figure 1 is a front view of an electrical receptacle showing my new design; and

Figure 2 is a horizontal axial section through the receptacle of Figure 1, to show the shape of the face of the receptacle.

I claim:

The ornamental design for an electrical receptacle substantially as shown.

REUBEN B. BENJAMIN.
